CLAIM

The ornamental design for a filter bag tensioning spacer, as shown and described.

DESCRIPTION

FIG. 1 is a top plan view of a filter bag tensioning showing my new design;

FIG. 2 is a side elevational view thereof, the opposite side being a mirror image of the side shown;

FIG. 3 is a bottom plan view thereof; and

FIG. 4 is another side elevational view taken 90 degrees to the left of FIG. 2, the opposite side being essentially the same as the side shown.

Fig. 1.

Fig. 2.

Fig. 3.

Fig. 4.
